UNITED STATES PATENT OFFICE.

CHARLES M. PLUM, OF SAN FRANCISCO, CALIFORNIA.

FURNITURE-SUPPORT.

SPECIFICATION forming part of Letters Patent No. 350,390, dated October 5, 1886.

Application filed June 2, 1886. Serial No. 203,965. (No model.)

To all whom it may concern:

Be it known that I, CHARLES M. PLUM, of the city and county of San Francisco, State of California, have invented an Improvement in Furniture-Supports; and I hereby declare the following to be a full, clear, and exact description of the same.

My invention relates to a device which is especially useful for the support of certain articles of furniture when not set up for actual use, such as the head and foot boards of bedsteads.

It consists of a narrow board or plate having latches or hooks upon each edge, so that it may be introduced between the head and foot board, the latches entering the openings which are ordinarily employed for holding the side rails in place when the bedstead is set up, and in connection with this I employ a support with casters, upon which the head and foot board may rest, standing close together, but just out of contact.

Referring to the accompanying drawings for a more complete explanation of my invention, Figure 1 is a view of my supporting device. Fig. 2 shows the device in connection with a stand upon casters. Fig. 3 shows its application to a head and foot board of a bedstead.

In the manufacture of furniture, while polishing and finishing it is necessary to move the parts about a great deal, and with bulky articles, like the head and foot board of a bedstead, they are difficult to handle, and are very apt to become injured by carelessness. When such furniture is set up in the wareroom on exhibition, it is either necessary to set up the bedstead with the side rails in place—in which case the set of furniture occupies much unnecessary room—or else the head and foot board lean against the wall, one leaning against the other, in which case they are very apt to become scratched or marred, and it is almost impossible to move them without injury.

My invention is designed to overcome these difficulties and provide a cheap and convenient support for these parts, so that they may be easily moved or transported from place to place without danger of injury and without occupying a great deal of space.

A is a strip of wood of sufficient width, so that when introduced between the outer ends

of the head and foot board of a bedstead it will just retain them out of contact with each other. Upon the edges of this strip are fixed plates of metal B, having hooks at their outer ends, so arranged as to fit into the sockets in the head and foot board, which are usually made to receive the hooks on the ends of the side rails of the bed when the whole is set up.

C and D represent the head and foot board of a bed, between which the piece or pieces A are fitted, and it will be seen that when this piece is in place the head and foot board will stand vertically parallel with each other and close together, being just out of contact, and having a sufficient base to support them firmly in position.

One of the fixtures A will be sufficient to hold the head and foot board in place; but it is better to have one at each end. In order to make it possible to easily move the pieces thus set up, I employ a standard, E, which is supported upon a base, F, of sufficient length to allow the ends of the head and foot boards C and D to rest upon it.

G is a loop or staple, which is fixed to the plate A, and fitted to slide down over the standard E, thus allowing it to adjust itself so that the ends of the head and foot board will rest upon the base F. This base has casters H, upon which it may roll easily, so that the whole device may be transported from place to place without difficulty.

I is a slotted opening or hand-hole in the upper part of the plate A, which is useful in putting it in or removing it when it is desired. During the manufacture of furniture the head and foot board may be set up and held by this plate A, either with or without the supporting caster-base F, and the workmen can then finish all parts without any difficulty, as they may stand in the middle of the room, so that access can be had to all sides. When they are to be transported in cars or other vehicles, they may be set up in the same manner, and a great number may thus be put into a carriage without any danger of contact, which would injure fine carving or finish, and a greater number may be safely transported in this way than in any other.

When set up in the wareroom, the same device serves to hold the head and foot board in its proper place, and they can be moved

out, so as to be examined, without danger of injury, and a very much larger number of pieces can be set up in a given space than by any other method.

5 Having thus described my invention, what I claim as new, and desire to secure by Letters Patent, is—

10 1. A device for supporting the head and foot board of a bedstead in vertical position when not in practical use, comprising the independent plates A, having the fixed hooks B, said plate being only of a width sufficient to retain the head and foot boards out of contact with each other, substantially as herein described.

15 2. The furniture-support composed of the plate A, with the hooks B, the socket G, in combination with the vertical standard, over which the socket slides, and the supporting-base mounted upon casters, substantially as 20 herein described.

3. A device for supporting the head and foot board of a bedstead in vertical position when not in practical use, consisting of a base mounted upon casters or wheels, having a standard projecting upwardly therefrom, in combination 25 with a narrow board or plate having a socket upon one side fitted to slide upon the standard, and having hooks or projections from opposite edges engaging corresponding sockets in the head and foot board, substantially as herein 30 described.

In witness whereof I have hereunto set my hand.

CHARLES M. PLUM.
